UNITED STATES PATENT OFFICE.

E. W. KIMBALL, OF OTTAWA, ILLINOIS.

IMPROVEMENT IN CORN-PLANTERS.

Specification forming part of Letters Patent No. 31,085, dated January 8, 1861.

To all whom it may concern:

Be it known that I, E. W. KIMBALL, of Ottawa, in the county of La Salle and State of Illinois, have invented a new and Improved Corn-Planter; and I do hereby declare that the following is a full, clear, and exact description of the same, reference being had to the annexed drawings, making a part of this specification, in which—

Figure 1 is a side sectional view of my invention, taken in the line $x x$, Fig. 2; Fig. 2, a plan or top view of the same; Fig. 3, a detached sectional view of a portion of the seed-slide.

Similar letters of reference indicate corresponding parts in the several figures.

This invention relates to an improvement in that class of corn-planters in which the seed-distributing device is placed on a mounted frame, and which are designed for planting in check-rows.

The invention consists in the employment or use of a reciprocating seed-slide in connection with valves placed in the lower parts of the seed-tubes and indicators connected to the valves, all being arranged substantially as hereinafter described, whereby the seed is dropped near the surface of the ground and the operation of the valves noted or indicated, so that the operator can instantly detect any failure in the dropping apparatus.

To enable those skilled in the art to fully understand and construct my invention, I will proceed to describe it.

A represents a rectangular frame, which is mounted on two wheels, B B, the latter being sufficiently wide to serve as rollers.

C is the driver's seat, which is attached to uprights $a a$ on the frame A at its back part; and D D are hoppers, which are placed on the front part of the frame, one at each side. The hoppers D D are connected by a board or seat, E, which is the operator's seat. The bottom b of each hopper has a circular opening, e , made in it, and on the bottom b of each hopper there is placed a slide, d . These slides work through the sides of the hoppers D, and they are connected at their inner ends to a bar, F, in which the lower end of a lever, G, is fitted, said lever passing through the seat E. The slides $d d$ are each perforated with two holes, $e e$, and in each slide d adjustable plates $f f$

are fitted, by which the holes e may be graduated, so as to be of greater or less area, as may be desired.

To the under side of the frame A there are attached runners H H, which open the furrows to receive the seed. These runners have openings g in them at their back ends. These openings extend entirely through the runners and form seed-tubes to convey the seed from the hoppers D D to the furrows.

In the lower end of each tube or opening g there is placed a flap or valve, I, the back ends of which are attached to rod J, which extend up back of the runners H and pass through guides h . Each rod J has a spiral spring, i , upon it, which springs have a tendency to keep the valves I closed and the lower ends of the openings g stopped. The rods J are acted upon by projections j at the under sides of the slides d . The projection of one side is shown clearly in Fig. 3.

The operation is as follows: As the machine is drawn along, the operator on seat E works the lever G first to the right and then to the left, and gives a reciprocating motion to the slides $d d$, and the seed in the hoppers D D is distributed by the holes $e e$ down into the openings or tubes g , the hoppers D being provided with the usual cut off-brushes, K. The valves I at the bottoms of the openings or tubes g catch each dropping of seed and discharge it, while the holes e in the bottoms b of the hoppers are covered by the slides d , the valves I being opened by the projections j of the slides d acting upon the rods J, the springs i closing the valves. The valves I cause the seed to be dropped from a point quite near the surface of the ground and all scattering of the seed is avoided.

To each rod J there is attached a wire or light rod, L. These rods L extend upward and back of the hoppers D D, and project upward sufficiently high to be seen by the operator. The rods L serve as indicators, and by their movement show that the valves I operate. By this arrangement the planting of the seed at all the desired points is insured.

In order to graduate the depth the seed is to be planted, I adjust the front part of the machine higher or lower by means of a pin, k , and perforated segment-bar l , the latter passing through a slot in the draft-pole M,

and the pin *k* passing through the draft-pole and perforated plate. This arrangement, however, has been previously used.

I do not claim separately the reciprocating seed-slides *d d* nor the cut off-brushes *K*, for such parts have been previously used; but

I do claim as new and desire to secure by Letters Patent—

The reciprocating seed-slides *d d* and valves

I I, when the latter are operated by the projections *j*, and the slides *d* and springs *l* on the rods *J*, and the latter provided with indicators or rods *L*, all arranged as and for the purpose herein set forth.

E. W. KIMBALL.
